UNITED STATES PATENT OFFICE

RICHARD R. CRAMER, OF MARION, INDIANA, ASSIGNOR OF ONE-HALF TO
JACOB F. KNEPPER, OF MARION, INDIANA.

BURIAL-CASKET.

No. 823,035.

Specification of Letters Patent.

Patented June 12, 1906.

Application filed June 30, 1905. Serial No. 267,712.

To all whom it may concern:

Be it known that I, RICHARD R. CRAMER, a citizen of the United States, residing at Marion, in the county of Grant and State of Indiana, have invented certain new and useful Improvements in Burial-Caskets, of which the following is a specification.

My invention relates to a new and useful improvement in burial-caskets.

10 The object of the invention is to provide a cement or plastic casket having embedded in its inner and outer surfaces suitable strips to which draperies and ornaments may be attached.

15 It is furthermore my object to provide a device of the character described that will be strong, durable, efficient and simple, and comparatively inexpensive to make.

With the above and other objects in view 20 the invention consists of the novel details of construction and operation, a preferable embodiment of which is described in the specification and illustrated in the accompanying drawings, wherein—

25 Figure 1 is a side elevation of my improved casket. Fig. 2 is a longitudinal vertical sectional view, and Fig. 3 is a transverse vertical sectional view taken on the line $z-z$ of Fig. 1.

In the drawings the numeral 1 designates 30 the casket-body, which is suitably shaped and formed from cement or any other suitable plastic material. In molding the casket-body the inner angle at the intersection of the sides and ends and the bottom is filled in, as indicated at 2, in order to strengthen 35 the structure at the said point. Near the top and bottom of the sides and ends of the body 1 I embed on the inside and outside continuous strips 3, preferably formed of wood, and having their exposed surface lying flush 40 with the surfaces of the said sides and ends. These strips 3 are dovetailed in cross-section and are placed in position when the casket-body is being molded. These strips are provided 45 for the purpose of receiving nails or tacks by which suitable ornaments and draperies may be secured to the casket. It will therefore be apparent that various soft materials other than wood might be employed. 50 In the upper and lower surface of the bottom of the casket-body I provide longitudinal strips 4, like the strips 3 and arranged in the same manner. From the foregoing it will be

obvious that adequate provision is made for 55 securely fastening draperies and other coverings to the casket-body. Along each side of the casket-body I embed suitable bolts 5, which project beyond the outer surface of the sides and provide means to which suitable handles may be secured. 60

A suitably-shaped cement lid 6 is provided on its under surface with a groove 7, adapted to receive the upper edges of the sides and ends of the casket-body, and thus efficiently 65 cover the same. If desired, suitable elastic 70 gaskets 8 may be arranged in the groove 7, so as to provide an air-tight joint. I embed in the upper portions of the sides and ends of the casket-body suitable bolts 9, which are adapted to project through the lid 6 and receive nuts 10 for the purpose of securely holding 75 the lid in place. Carrying out the usual construction of a casket, I provide the lid 6 near one end with a sight-opening, around which is formed a ledge 11, adapted to receive a pane of glass or other transparent sheet 12. About the opening I embed bolts 13, projecting upwardly and adapted to pass through the reduced edges of a cover-panel 14, which is fastened down over the glass by 80 means of nuts 15, engaged on the bolts 13. This panel 14 may be removed and a view of 85 the face of the corpse had. The lid of the casket, as well as the panel-cover, may be suitably draped or covered and the scheme 90 of ornamentation carried out, as it will be apparent that by draping and covering the casket-body the same is ornamented and given an artistic appearance, which relieves it of the unsightliness where the cement or plastic material is exposed to view.

Having now fully described my invention, what I claim, and desire to secure by Letters Patent, is—

A cement or plastic burial-casket having 95 strips of soft material embedded in its inner and outer surfaces, the exposed portions of the said strips lying substantially flush with the said surfaces.

In testimony whereof I affix my signature 100 in presence of two witnesses.

RICHARD R. CRAMER.
